UNITED STATES PATENT OFFICE.

BERNIE C. KRIDLER, OF FLINT, MICHIGAN, ASSIGNOR, BY DIRECT AND MESNE ASSIGNMENTS, TO THE SHINGLE LOCK COMPANY, OF FLINT, MICHIGAN, A CORPORATION OF MICHIGAN.

ROOFING SHINGLE.

Application filed November 16, 1921. Serial No. 515,216.

To all whom it may concern:

Be it known that I, BERNIE C. KRIDLER, a citizen of the United States of America, and a resident of Flint, in the county of Genesee and State of Michigan, have invented certain new and useful Improvements in a Roofing Shingle, of which the following is a specification.

Among the principal objects which the present invention has in view are: To construct roof covering of shingles without the aid of fastening devices driven therethrough; to reduce the time factor required for installing the shingles in service relation; to improve the alignment of shingles when installed in service; to avoid splitting the shingles used for roof covering; and to secure the same in service relation.

Drawings.

Figure 1 is a sectional view showing the service relation of shingles when disposed in roof covering and constructed and arranged in accordance with the present invention.

Figure 2 is a top view of a shingle constructed and arranged in accordance with the present invention.

Figure 3 is a side edge view of the same.

Figure 4 is an end edge view of the same.

Figure 5 is a bottom view of the same on reduced scale.

Figure 6 is an edge view of shingles constructed in accordance with the modified form of the invention.

Figure 7 is a side edge view of the shingle the lock member being constructed in accordance with a further modification of the invention.

Figure 8 shows a different modification of the retaining lug of the shingles, constructed in accordance with the present invention.

Description.

Heretofore, shingles or roofing tile have been mounted or secured on roofing structure to form a covering therefor, using as retaining devices, nails or other metallic driving members. A considerable loss has been experienced owing to accidents occurring such as would be occasioned by the mechanic striking the body of the shingle with his

hammer or when the shingle has been constructed of brittle or fragile material by breaking the same with punching instruments used in connection therewith. Another objection which has been found has resided in the fact that the shingles have been often cracked lengthwise, the fracture not being at the time observed and only discovered when frost or ice has entered the fracture and spread the same, converting it from a somewhat innocent, to a vicious leak in the roof covering.

The principal object of the present invention is to overcome these defects. To that end each shingle 15 is provided with one or more holding lugs 16. The lugs 16 are preferably disposed adjacent the edge of the shingle and spaced apart to provide a channel 17 therebetween. The lugs 16 as may be seen best in Figures 2 and 5 are aligned in transverse relation to the shingle and are adapted for engagement by a straight furring strip or narrow sheathing board 18.

The sheathing boards 18 are forced down on the lugs 16 before driving the screws 19 or other fastening devices into the rafters 20 of the roof structure.

When using shingles constructed and arranged in accordance with the present invention the rafters 20 are preliminarily provided with a course board 21 secured to the rafters at the ends thereof to form the eaves of the roof. Before laying the first course of shingles 15, a furring strip 22 is secured to the course board 21 adjacent the lower exposed edge thereof. The strip 22 is engaged to support the free end of the shingle 15 when the lower edges of the lugs 16 rest on the rafters 20 as shown. Should the lugs fall between the rafters, then the shingles will be supported by the superposed sheathing board 18. The first sheathing board 18 is then introduced and disposed behind or above the lugs 16 on the first course of shingles. While the sheathing board 18 is held firmly in place, the screws 19 are driven home. The boards 18 are equal in width and constitute gages for setting the various courses of tiles, that is to say, the width of the board 18 plus the length of the lugs 16, equals the exposed surface of each course of tiles.

The second course of tiles is then disposed so that the lugs 16 thereof rest on the sheathing board 18, which has just been disposed in place, the skirt of the second course of shingles overhanging the butts of the first course of shingles. The usual practice of staggering the joints between shingles is pursued when covering a roof with shingles herein described.

10 The shingles are thus laid, course by course, the sheathing boards being permanently secured to the rafters 20 as the covering approaches the ridge of the roof.

While I prefer the straight-sided lugs 16 as shown in Figures 1 to 5, inclusive, it will be understood that if greater security in the lock is desired, lugs having ends shaped as shown in Figures 6, 7 and 8 may be employed. Whenever lugs of this character are employed, it will be recognized that the edges of the sheathing boards 18 will conform with the recesses 16', 16'' or 16''' of the lugs formed in the modifications.

Claims.

25

1. In combination, a roof structure including equidistantly spaced straight edged sheathing strips each of an even thickness, and a shingle comprising a body, and a lug 30 formed on the under side of said body and adapted to snugly fit between the opposed edges of said sheathing strips.

2. In combination, a roof structure including equidistantly spaced straight edged 35 sheathing strips each of an even thickness, and a shingle comprising a body, and lugs spaced apart transversely of the under side of said body and adapted to snugly fit be-

tween the opposed edges of said sheathing strips.

3. In combination, a roof structure including equidistantly spaced straight edged sheathing strips each of an even thickness, and a shingle comprising a tapered body, and lugs spaced apart transversely of the under 45 side of said body and adapted to snugly fit between the opposed edges of said sheathing strips.

4. In combination, a roof structure including equidistantly spaced straight edged 50 sheathing strips, and a shingle comprising a tapered body, and lugs spaced apart transversely of the under side of said body and adapted to snugly fit between the opposed edges of said sheathing strips, said lugs being grooved to admit of the free circulation of air beneath the shingle and to otherwise reduce the weight of the same without materially decreasing the strength thereof.

5. In a roof structure, straight edged 60 sheathing strips spaced equidistantly apart, one parallel to the other, shingles adapted to be laid on said sheathing strips, said shingles being tapered whereby to flatly contact one in overlapping relation with the other, and a 65 lug formed on the under sides of said shingles and adapted to snugly fit between the opposed edges of adjacent sheathing strips, the width of the sheathing strip engaging the upper side of a lug combined with the 70 length of the lug itself approximating the length of the exposed surface of a shingle whereby to uniformly gage the shingles laid in successive rows on the roof structure.

BERNIE C. KRIDLER.
